UNITED STATES PATENT OFFICE

2,480,408

ADVERTISING SIGN

Ira W. Fuller, Roxbury, Mass.

Application April 4, 1945, Serial No. 586,537

4 Claims. (Cl. 40—140)

1

This invention relates to painted signs and especially to advertising signs having raised characters, letters, or symbols which are sometimes referred to as "embossments."

In order to maintain in satisfactory condition a painted advertising sign that is located out of doors, it is necessary to repaint it periodically. If the sign is a large one and is placed on top of a building or in some other more or less inaccessible place, the operation of repainting the sign presents a more or less difficult problem.

It is one of the objects of my present invention to provide a novel painted advertising sign which is so constructed that the painted surface thereof can be quickly and easily renewed. This end is accomplished by making the letters, characters, or other symbols constituting the sign detachable from their supporting background and by forming each letter, character, or symbol with a skeleton framework which is provided with a detachable envelope of painted fabric. The background to which the letters or symbols of the sign are attached is also preferably made with a skeleton frame which is covered by a detachable painted fabric envelope.

With my invention the renewing of the painted surface of the sign can be accomplished by demounting the individual letters, characters, or symbols of the sign from the background, removing the worn painted envelope for each letter or symbol and replacing such worn envelope with a freshly painted envelope, after which the individual letters or symbols with their freshly painted envelopes can be replaced on the supporting background.

If it is desired to renew the surface of the supporting background, this can be easily done by removing the old worn envelope covering the skeleton framework of the background and replacing this by a freshly painted envelope. The painting of the envelopes for the letters, characters, or symbols of the sign and also for the supporting background can be done in a paint shop or in any convenient location, and the operation of applying freshly painted envelopes or coverings to the skeleton frame of any letter or symbol is a simple matter which can be quickly accomplished. The construction is also such that the matter of demounting any letter or symbol from its background or replacing it thereon is a simple operation which can be readily carried out.

In order to give an understanding of my invention, I have illustrated in the drawings some selected embodiments thereof, which will now be

2

described after which the novel features will be pointed out in the appended claims.

In the drawings:

Fig. 1 is a fragmentary perspective view of a portion of a sign having a raised letter thereon embodying my invention.

Fig. 2 is a perspective view of the skeleton frame for the letter "U".

Fig. 3 is a section taken on the line 3—3, Fig. 5.

Fig. 4 is a perspective view showing the framework for the letter "I" of a sign embodying my invention with a portion of the envelope applied thereto, the view being taken from the front.

Fig. 5 is a similar view taken from the back.

Fig. 6 is a fragmentary view showing the detachable fastener at the top of each letter.

Fig. 7 is a view on the line 7—7, Fig. 6.

Fig. 8 is a side view and Fig. 9 is a perspective view of one member of the detachable fastener used at the bottom of the letter.

Fig. 10 is a fragmentary view showing the way in which the wires of the skeleton frame are joined.

The sign illustrated in Fig. 1 comprises a background element 1 on the front of which is mounted a plurality of letters, characters, or symbols 2, which constitute the sign, the letter "U" being shown in said Fig. 1.

The background element 1 comprises a skeleton framework 3, preferably made of wire and comprising a plurality of wires 4 which extend longitudinally of the background and other wires 5 which extend vertically thereof, said wires 4 and 5 being spot-welded or otherwise fastened together at the points 60 where they cross each other. This skeleton frame is covered by an envelope element 6, preferably of canvas or some other fabric which is suitably painted, thereby providing a background element having a painted surface.

If it is desired that the background element should give the appearance of a raised background, then the end portions of the wires 4 and 5 will be bent backwardly as indicated at 7, so as to give a proper depth to the background, the rear ends of the backwardly bent portions 7 being connected by wires 4a, 5a which correspond to the wires 4 and 5 on the front face of the frame.

Each letter, character or symbol of the completed sign is separately and detachably mounted on the background element. Each of these characters of the sign comprises a skeleton framework, preferably of wire, which is covered by an envelope of painted fabric.

In the case of the letter "U" as seen in Figs. 1

and 2, the skeleton framework is indicated generally at 8 and the painted fabric covering at 9. The skeleton framework 8 is formed of a plurality of strands of wire 8a which are bent to the U shape and which are connected by the transverse wires 8b, said wires being so fabricated as to form a skeleton frame having the U shape and also having a desired depth, so that when the skeleton framework is covered by the envelope 9 and the letter is applied to the background, said letter will stand out from the background and constitute a raised letter.

In Figs. 4 and 5 I have illustrated more in detail the construction of the skeleton framework for the letter "I". This framework comprises front and rear wire elements 10, 10a extending from the top to the bottom of the letter and connected by U-shaped transverse wires 11. The wire elements 10 together with the bridge portions 11a of the top and bottom transverse wires 11 constitute a bounding wire which bounds the front face of the symbol. The rear vertical wires 10a are connected at the top and bottom by wires 31, and said wires 10a together with the top and bottom connecting wires 31 bound the rear of the symbol.

The ends of the leg portions of the intermediate U-shaped wires 11 are welded to the rear vertical wires 10a at 32a and each leg is located in the plane of the two wires 10 and 10a at the side of the symbol. The bridge portion 11a of each U-shaped wire 11 which connects the two legs thereof is located in the plane of the front bounding wires 10. Each U-shaped wire 11 is bent inwardly at 32 where each leg joins the bridge portion and said inwardly bent portion 32 extends around inside of the vertical wires 10 as best seen in Fig. 3.

If desired, additional vertical wires 10c may be used in each side of the skeleton framework, and said wires 10c are located in the plane of the wires 10, 10a. Each leg of the U-shaped wire 11 is deformed or bent inwardly as shown at 31a to extend around the inside of each of the intermediate wires 10c. All of these wires will be welded together to make a rigid one-piece skeleton frame and by the construction shown best in Fig. 3, a skeleton frame is provided which has a smooth outside face free from any bumps or projections caused by the union of the wires where they cross. This results from the construction wherein each leg of the U-shaped wires 11 is located in the plane of the corresponding wires 10, 10a, while the bridge portion 11a of each U-shaped wire 11 is located in the plane of the two wires 10 at the front of the symbol.

The painted fabric envelope for the letter "I" is indicated at 9 and it is made to fit around the front and side faces of the frame as best seen in Fig. 3. The edges 12 of the envelope are folded around the rear vertical wires 10a and the top and bottom connecting wires 31 and may be stitched or secured to the main body of the fabric in any suitable way as indicated at 13. The fabric envelope covers only the front, the sides, the top and the bottom of the skeleton framework of any letter or symbol, the back being open as clearly seen in Figs. 3 and 5. Since the frame is made so that it presents a smooth exterior surface, the envelope when applied to the frame will have a smooth surface and be free from any unevenness that might mar its effect in the sign. This same construction may be used in connection with any of the letters or other symbols or characters constituting the sign and each symbol

or character will, therefore, present a hollow wire skeleton frame which is covered on the front, the top, the bottom, and the sides by the painted fabric covering but which is open at the rear. A figure or letter or symbol of this construction is relatively light in weight and even a large letter can be readily handled.

Suitable means are provided for detachably securing each letter or symbol to the background element, and while any desired means may be employed, I prefer to use the attaching means herein illustrated.

The background element is provided near its lower end with a plurality of studs 15 which are shown as mounted on supporting wires 16 of the skeleton framework for the background and which are properly spaced to receive the various letters, symbols, etc. The skeleton framework of each letter or symbol carries near its lower end a socket fastener element 17 which is adapted to be snapped over the corresponding stud 15. The fastener elements 15, 17 may have any suitable construction such as are commonly used for glove fasteners or other snap fasteners. In Fig. 5 the socket fastener element 17 is shown as mounted on supporting wires 18 which are spot-welded to the skeleton wire frame.

The skeleton framework for each letter also has at its upper end a retaining loop member 19 of wire presenting two parallel legs 33 which are adapted to receive between them the shank of a headed stud 20 with which the skeleton frame for the background is provided. These headed studs 20 are shown as mounted on supporting wires 22 with which the skeleton framework is provided, and they are properly situated or placed to co-operate with the legs 33 of the retaining loop 19 of the various letters.

In securing any letter or symbol to the background, the letter will be manipulated so that the shank of one of the headed studs 20 of the background will be entered into the space between the legs 33 of the loop 19 of the letter, and then the letter is further manipulated to bring the socket fastener element 17 into register with the corresponding stud element 15 and the stud and socket are snapped together. The letter is by this means firmly secured to the background element but can be readily removed by disconnecting the snap fasteners 15, 17 and then lifting the letter sufficiently to carry the loop 19 off from the corresponding headed stud 20. When each letter or symbol is thus secured to the background element, the back face of the letter or symbol will be in contact with and resting against the front face of the background as clearly seen in Fig. 1.

A similar construction may be used for removably mounting the background element on its support and in Fig. 1 I have shown a socket element 17a at the lower corner of the skeleton frame 3 for the background element and an open loop 19 near the top of said skeleton framework. The support to which the background element is to be secured will be provided with suitable studs to receive the socket element 17a and with other suitable headed studs to co-operate with the loop 19.

Whenever it is desired to renew the painted surface of the sign embodying my invention, all that is necessary is to demount the letters, characters or symbols from the background, remove the worn or faded envelope from each letter or symbol and re-cover the skeleton frame of each letter with a newly painted envelope or cover.

When this has been done, the renewed letters can be easily and quickly remounted on the background.

If it is desired to renew the painted surface of the background element, then the latter can be readily demounted from its support and the faded or worn envelope can be removed from the skeleton frame of the background and a freshly painted envelope applied to such skeleton frame. Because of the skeleton frame construction, the individual letters even in a large sign are relatively light and can be easily handled, and the same is true with respect to the background element.

Where a sign is of a permanent character, that is not to be changed for a long time, it would be possible to prepare a plurality of envelopes for each symbol or letter of the sign and have these on hand so that the stock of prepared envelopes could be drawn on whenever it was thought best to renew the surface of the sign.

These envelopes can be painted by hand or by the silk screen process or in any other desirable way.

With the construction herein shown the means for fastening the separate letters or symbols to the background are entirely concealed and similarly the means for securing the background to its support will be concealed behind the background.

I claim:

1. An advertising sign comprising a supporting background element, a plurality of symbol elements each having a skeleton framework of wire presenting wires which bound the symbol at both the front and back, and also presenting U-shaped transverse wires, each leg of each transverse wire being connected to the vertical bounding wires at the rear of the symbol and being situated in the plane of the two bounding wires at the corresponding side of the symbol, the bridge portion of each transverse wire being located in the plane of the front bounding wires, said transverse wires being bent inwardly where each leg meets the bridge portion to partially encircle the inside of the front bounding wire, said bounding and transverse wires being welded where they cross or meet each other, said wire framework thereby presenting smooth faces, a fabric envelope covering the front, each side, the top and bottom of each skeleton framework, each symbol being open at the back, and means for detachably securing each symbol to the background.

2. An advertising sign comprising a background element having a skeleton framework of wire and a fabric envelope covering said framework, a plurality of symbol elements, each also having a skeleton framework of wire and an envelope of fabric covering the front, each side, and top and bottom of the skeleton framework, the back of the latter being uncovered, each symbol element having at the upper end of its open back side an inverted U-shaped attaching member and said background element having at its front face a projecting stud on which the U-shaped attaching element of the symbol may be hung, and a separable fastener for detachably securing the bottom of each symbol element to the background element.

3. An advertising sign comprising a supporting background element, a plurality of symbol elements each having a skeleton framework presenting wires which bound the symbol at both the front and the back, and other intermediate transverse wires located between the top and bottom of the symbol and extending transversely to and connecting the bounding wires at the sides and at the front only, the back of the skeleton framework being free from such intermediate transverse wires and thus being open and unobstructed, an envelope of fabric covering the front, each side, the top and the bottom only of the skeleton framework, the edges of the fabric covering being folded about the bounding wires at the back of the framework and secured to the body of the fabric, the back of the framework which is free from said intermediate transverse wires being uncovered and therefore also free from said fabric covering, and separable fasteners for removably securing each symbol element to the background element, each fastener comprising two separable parts one of which is permanently mounted on the background element, and the other of which is permanently mounted on the skeleton framework of the symbol.

4. An advertising sign comprising a supporting background element, a plurality of symbol elements each having a skeleton framework presenting wires which bound the symbol at both the front and the back, and other intermediate transverse wires located between the top and bottom of the symbol and extending transversely to and connecting the bounding wires at the sides and at the front only, the back of the skeleton framework being free from such intermediate transverse wires and thus being open and unobstructed, an envelope of fabric covering the front, each side, the top and the bottom only of the skeleton framework, the edges of the fabric covering being folded about the bounding wires at the back of the framework and secured to the body of the fabric, the back of the framework which is free from said intermediate transverse wires being uncovered and therefore also free from said fabric covering, and separable fasteners for removably securing each symbol element to the background element, with the back face of the symbol element in contact with the background element, each fastener comprising two separable parts one of which is permanently mounted on the background element, and the other of which is permanently mounted on the skeleton framework of the symbol.

IRA W. FULLER.
